UNITED STATES PATENT OFFICE.

LYMAN C. DAVIDSON, OF CHICAGO, ILLINOIS.

FASTENER FOR BOX-CLOSURES.

1,222,367.

Specification of Letters Patent. Patented Apr. 10, 1917.

Application filed June 3, 1916. Serial No. 101,474.

To all whom it may concern:

Be it known that I, LYMAN C. DAVIDSON, a citizen of the United States, residing at Chicago, in the county of Cook and State 5 of Illinois, have invented a certain new and useful Improvement in Fasteners for Box-Closures, of which the following is a specification.

This invention is a device for closing and 10 sealing boxes of any and all kinds, where a perfect air-tight closure is desired, with special references to devices of this kind, such as bread boxes, sugar boxes, humidors, and so forth, where ready and repeated opening 15 and closing of the box is required. For convenience, the drawings show, and the invention will be described, as applied to a portable humidor for handling cigars.

The object of this invention is to provide 20 a device of this kind in which the ordinary user can, by manipulating an accessible and readily handled part, apply a very heavy pressure to force the cover and body of the receptacle together, thereby effecting a satisfactory sealing of the device.

The invention consists in a device capable 25 of carrying out the foregoing objects, which can be easily and cheaply made, which is efficient in operation and not liable to get out of order. It consists more particularly in 30 a novel form of concealed spring construction for forcing the cover onto the receptacle, in combination with special means co-operating with the springs for producing the 35 desired result. The invention consists further in the special features and details more fully described in the specification and claims.

Referring to the drawings, in which similar numerals indicate the same parts throughout the several views,

Figure 1 is a perspective view of a closed humidor having the device of this invention applied thereto.

Fig. 2 shows the parts of Fig. 1 in the position which they assume when the cover is removed from the humidor.

Fig. 3 is a side view partially in section of the parts of Fig. 1 in a changed position 50 intermediate between those of Figs. 1 and 2.

Fig. 4 is a sectional detail view on the line 4-4, of Fig. 1.

Fig. 5 is a sectional detail view on the line 5-5, of Fig. 3.

Fig. 6 is a detail plan view taken on the line 6-6, of Fig. 3.

Fig. 7 is a sectional view showing a novel way of forming a packing ring recess.

Fig. 8 shows a sectional view of a detail.

The box or case to be closed, in this particular set of drawings a humidor, designed to be carried in a suit case or grip, consists of a rectangular body portion 10 closed by a correspondingly shaped cover member 12, the edge 13 of one of these parts (the cover 60 12) fitting into a recess 14 formed in the other, the bottom of this recess being provided with a packing cushion 15.

The cover 12 is made with hollow walls throughout; that is to say, with parallel side 70 walls 16 and 18 between which there are air spaces 20 communicating with a top air space 22 formed between the exterior top wall 24 and an interior wall 26. Extending across the cover through the space 22 is a 75 bar or shaft 30 whose ends project through and move vertically in vertically elongated slots 32 in opposite outside walls 18 of the cover. This bar 30 is pressed upward by a pair of elliptic springs 34, one located in the 80 space 20 on each side of the cover, the ends of the springs being adapted to travel horizontally on flat trackways formed on the interiors of the lower edge 13 of the cover in the manner which is entirely obvious from 85 an inspection of Fig. 3. In other words, these springs are retained in inclosed chambers in the side walls which, while permitting movement of the springs, retain them against removal. These springs 34 are made 90 very strong, those in one sample of the device heretofore made being sufficiently powerful to provide ten pounds pressure on each inch of circumferential length about the bottom edge of the cover or top edge of the 95 case when the parts are assembled.

Projecting from opposite sides of the case 10 and immediately below the bar 30 are stationary pivot pins or screws 36 located in alignment with each other on opposite 100 sides of the case. Journaled on these pins 36 are opposite ends of a U-shaped hand lever 40, designed to be left in the position of Fig. 1 when the device is closed and in the position of Fig. 2 when the device is open. Rigid 105 with each end of lever 40 is an eccentric 42. On the circumference of each eccentric 42 is journaled a latch arm 44 having on its outer end a hook 46 adapted, when in the position of Fig. 1, to fit over the adjacent end 110 of the bar 30. Eccentric 42 is so adjusted, with reference to the ends of U-shaped lever

40, that when the lever 40 is in the position shown in Fig. 3, or slightly to the left thereof, the eccentrics 42 will begin to move the arms 44 downward, and as the lever 40 moves in a clockwise direction from the position of Fig. 3, they will continue to do so until the parts reach the position of Fig. 1, with the result that the bar 30 has been moved downward the lengths of the slots 32, thereby compressing the springs 34 and securing the cover on the case under the pressure of said springs 34. The arms 44 are provided with stops 50 so located and arranged that the maximum rotative travel of the arms 44 is only between the positions of Figs. 1 and 2; or, in other words, through an arc of about ninety degrees.

In order to enable the lever 40 to move the arms 44 from the position of Fig. 2 to that of Fig. 3 without securing them together, which is impossible in view of the movements heretofore described of the parts with reference to each other, the tops of the members 46 are provided with a cam track composed of the parts 52 and 52^a, arranged as shown, and the opposite side members of the U-shaped lever 40 are provided with movable plunger heads 54, slidably mounted in the side arms of the lever 40 in such a position that projecting portions of said plunger heads 54 engage the cam tracks 52 and 52^a in the manner and for the purposes hereafter described. Each plunger head 54 illustrated in section in Fig. 6 is broader than a stem portion 54^a, integral therewith and adapted to move longitudinally of an elongated slot 58 cut in the adjacent arm 40. This slot 58 is narrower than and below another slot 60 also cut in said arm 40 and communicating with the slot 58 so that the stem 54^a of the plunger head can reciprocate in the two slots against the action of spring 56, said spring being held in place by oppositely disposed caps or covers 62 placed on opposite sides of the lever 40 and suitably secured in position, as, for instance, by soldering. The slot 60 is in fact longer than the slot 58, so that in assembling the parts, the plunger head 54 may be placed bodily in the slot 60 before the stem 54^a is moved downward to the position shown in the drawings, with the plunger head 54 engaging both sides of the lever 40, thereby preventing its removal.

In the operation of the device, assume that the parts are in the position shown in Fig. 2. The cover 12 is moved down onto the case 10; *i. e.*, to the position shown in Fig. 1, with the lever 40 and arm 44 still in the position of Fig. 2. The operator now takes hold of lever 40 and starts to move it in a clockwise direction toward the position of Fig. 3; in so doing the plunger heads 54 very speedily engage cam tracks 52—52^a, which are so located that in the absence of obstruc-

tions to the arms 44, the plungers 54 are behind and, therefore, move the levers 44. As soon as the levers 44 reach the position shown in Fig. 1, with the ends of rod 30 under hooks 46, thus creating an obstruction to the further movement of the arms 44, sufficient resistance to these arms is encountered, so that plunger heads 54 travel up cam surfaces 52^a and onto surfaces 52, being frictionally held there by the springs 56. During the time that lever 40 is moving through the arc represented by the lengths of the cam surfaces 52, this frictional engagement of the plungers with said surfaces 52 continues, consequently holding the hook devices 44—46 in the position shown in Fig. 1 for a sufficient length of time until, the eccentric cam, heretofore described, has moved the arms 44 sufficiently downward against the action of the springs 34 to prevent escape of the hooks 46 from the ends of bar 30. Further movement of the lever 40 to the position which it assumes in Fig. 1 merely further compresses the springs 34 and positively locks the cover on the case; that is to say, holds the cover on the case under the pressure of the springs 34.

In reversing the operation, the lever 40 moves from the position of Fig. 1 toward that of Fig. 3 and finally to that of Fig. 2; the first portion of this movement, of course, releases the spring pressure on the hook devices 44—46, until, at the end of which operation the plunger heads 54 frictionally engage the cam surfaces 52 sufficiently to move hooks 46 off from the ends of rod 30, and the hooks continue to move with the lever 40 until they are stopped by the members 50 reaching the position of Fig. 2, whereupon, as the lever 40 continues to move in a counter-clockwise direction, the plungers 54 travel entirely off from cam tracks 52—52^a, and the parts assume their initial position of Fig. 2, ready to have the operation repeated.

In the particular design of the device here illustrated, the greatest locking effect or pressure of the cover on the case is in the position shown in Fig. 1, where the bottom of the U-shaped lever 40 is in substantial contact with the side wall of the case, and there is, therefore, little danger of the lever being accidentally engaged by external objects to release the lock.

The use of the U-shaped lever is very important, because it enables the operator, by a single movement of the hand, to exert a predetermined, uniform securing or locking pressure on both sides of the case and secure results which could not be obtained were independent locking or securing devices separately manipulably arranged on opposite sides of the case.

It is important that the rod 30 be secured to each of the springs 34, thereby insur-

ing ready operation of the device and preventing the friction which would occur were the springs not connected together and only short studs projecting from the springs provided in the place of the ends of the rod 30.

Fig. 7 shows the novel method of constructing a U-shaped recess for the rubber washer 15 on the upper edge of the case 10, while maintaining the wall of the case entirely imperforate, the method employed 10 greatly simplifying the methods heretofore used. In doing this, the metal sheet 70 is bent first outward in the line 72, then upward in the line 74, parallel to 70, thence 15 inward in the line 76, and finally upward in the line 78, lying in the same plane as portion 70. On the outside of portion 74 a supplemental plate 80 is riveted to a block or bar of iron 82, placed within the recess 20 inclosed by portions 72, 74 and 76, of sheet metal, such rivet being shown as 84.

The iron member 82 provides a general stiffening for the box and an anchorage for the studs 36.

This construction has the distinct advantage over prior constructions in that a perfectly tight joint, *i. e.*, integrality, is maintained at the corner 86, so that air coming 25 from the inside of the case over the edge of member 78 cannot get through at this point.

Fig. 8 shows the novel method of constructing the hollow cover 12 of this device, in which the bottoms of the side walls 16 and 18 are respectively curved toward each 30 other and about the bearing member 13, heretofore described, in the curved forms 16^a and 18^a and assembled in the position generally shown in Fig. 8, after which they are driven together into the position shown in 40 Fig. 4, thus making an air-tight joint at the contact of the parts 16^a and 18^a.

Having thus described my invention, what I claim as new and desire to secure by Letters Patent, is:—

1. In a device of the class described, a case and a cover to be secured together, means for drawing one of said members toward the other, and a metallic spring device located in an inclosed chamber formed in one of said parts to be secured together resisting the operation of said drawing means, for the purposes described.

2. In a device of the class described, the combination of a case and cover to be secured together, means for drawing said members together, one located on each side of the device, metallic spring devices located on opposite sides of one of said members to be secured together simultaneously resisting the 50 operation of said drawing means.

3. In a device of the class described, the combination of a case and cover to be secured together, means for drawing said members together, one located on each side of the device, metallic spring devices located

on opposite sides of one of said members, to be secured together, simultaneously resisting the operation of said drawing means, and a single operating means for simultaneously manipulating said drawing means. 70

4. In a device of the class described, a case and a cover to be secured together, means for drawing one of said members toward the other, and a spring device located and movable within an inclosed chamber 75 formed in one of said parts to be secured together, having a connecting means extending outside said chamber engaging and resisting the operation of said drawing means, for the purposes described. 80

5. In a device of the class described, the combination of a case and cover to be secured together, means for drawing said members together, one located on each side of the device, spring devices located and 85 movable in inclosed chambers in walls on opposite sides of one of said members to be secured together simultaneously resisting the operation of said drawing means.

6. In a device of the class described, the combination of a case and cover to be secured together, means for drawing said members together, one located on each side of the device, spring devices located and 90 movable in inclosed chambers in walls on opposite sides of one of said members, to be secured together, simultaneously resisting the operation of said drawing means, and a single operating means for simultaneously 95 manipulating said drawing means. 100

7. In a device of the class described, a case and a cover to be secured together, means for drawing one of said members toward the other, a spring device located within an inclosed chamber formed in one 105 of said parts to be secured together, and means connected to said spring extending through a slot in the wall of said chamber engaging and resisting the operation of said drawing means, for the purposes set forth. 110

8. In a device of the class described, the combination of a case and cover to be secured together, means for drawing said members together, one located on each side of the device, spring devices located, in inclosed chambers, on opposite sides of one 115 of said members to be secured together, and means connected to said springs extending through slots in the walls of said chambers engaging and simultaneously resisting the 120 operation of said drawing means.

9. In a device of the class described, the combination of a case and cover to be secured together, means for drawing said members together, one located on each side 125 of the device, spring devices located, in inclosed chambers, on opposite sides of one of said members, to be secured together, and means connected to said springs extending through slots in the walls of said chamber. 130

1. members engaging and simultaneously resisting the operation of said drawing means, and a single operating means for simultaneously manipulating said drawing means.
- 5 10. In a device of the class described, a case and a cover to be secured together, means for drawing one of said members toward the other, an elliptic spring device located within an inclosed chamber formed 10 in one of said parts to be secured together, and means connected to said spring extending through a slot in the wall of said chamber engaging and resisting the operation of said drawing means.
- 15 11. In a device of the class described, the combination of a case and cover to be secured together, means for drawing said members together, one located on each side of the device, elliptic spring devices located 20 in inclosed chambers, on opposite sides of one of said members to be secured together, and means connected to said springs extending through slots in the walls of said chambers engaging and simultaneously resisting the operation of said drawing means.
- 25 12. In a device of the class described, the combination of a case and cover to be secured together, means for drawing said members together, one located on each side of the device, elliptical spring devices located 30 in inclosed chambers, on opposite sides of one of said members, to be secured together, and means connected to said springs extending through slots in the walls of said 35 chambers engaging and simultaneously resisting the operation of said drawing means, and a single operating means for simultaneously manipulating said drawing means.
- 40 13. In a device of the class described, the combination of a case, a cover adapted to close the case, said cover being provided with hollow recessed side walls and a top, a pair of springs, one located in each of the recesses located in two opposite side walls 45 of the case, a bar rigidly connected to said springs extending through and adapted to move in slots in the outer walls of the cover elongated in the direction of the case, hook devices carried by cams on opposite sides 50 of the case and adjacent to the ends of said bar adapted to swing over the ends of said bar, and means for simultaneously manipulating said cam devices to cause said hooks to draw the cover and case together against 55 the action of said springs.
- 60 14. In a device of the class described, the combination of a case, a cover adapted to close the case, said cover being provided with long and narrow hollow recessed side walls, a pair of elliptic springs, one located in each 65 of the recesses located in two opposite side walls of the case, a bar rigidly connected to said elliptic springs extending through and adapted to move in slots in the outer walls 70 of the cover elongated in the direction of
- the case, hook devices carried by cams located on opposite sides of the case and adjacent to the ends of said bar adapted to swing over the ends of said bar, and means for simultaneously manipulating said cam 75 devices to cause said hooks to draw the cover and case together against the action of said elliptic springs.
15. In a device of the class described, in combination with a case and cover having abutting side walls, an operating lever pivoted to one of said members in proximity to the other, an eccentric cam carried and movable by said lever, a hook device loosely journaled on said eccentric cam adapted to swing 80 thereon from a position where it does not overlap the second of said first mentioned members to a position where it does so, means limiting the swing of the hook device so that it moves through a shorter arc 85 than the lever, and a frictional contact device carried by the lever, adapted to temporarily engage the hook as the lever swings through the hook's arc of movement to carry 90 said hook with it.
16. In a device of the class described, in combination with a case and cover having abutting side walls, an operating lever pivoted to one of said members in proximity to the other, an eccentric cam carried and movable by said lever, a hook device loosely journaled on said eccentric cam adapted to swing 95 thereon from a position where it does not overlap the second of said first mentioned members to a position where it does so, means limiting the swing of the hook device so that it moves through a shorter arc than the lever, and a frictional contact device carried by the lever adapted to temporarily engage the hook as the lever swings through 100 the hook's arc of movement to carry said hook with it, the eccentric cam being so located with reference to the hook that when the hook has reached its extreme position, overlapping the second of said first mentioned members, it draws said hook in the 110 direction of the member on which the lever is pivoted.
17. In a device of the class described, in combination with a case and cover having abutting side walls, an operating lever pivoted to one of said members in proximity to the other, an eccentric cam carried and movable by said lever, a hook device loosely journaled on said eccentric cam adapted to swing 115 thereon from a position where it does not overlap the second of said first mentioned members to a position where it does so, means limiting the swing of the hook device so that it moves through a shorter arc than 120 the lever, and a frictional contact device carried by the lever adapted to temporarily engage the hook as the lever swings through the hook's arc of movement to carry said hook with it, the eccentric cam being so located 125 with reference to the hook that when the hook has reached its extreme position, overlapping the second of said first mentioned members, it draws said hook in the direction of the member on which the lever is pivoted.
18. In a device of the class described, in combination with a case and cover having abutting side walls, an operating lever pivoted to one of said members in proximity to the other, an eccentric cam carried and movable by said lever, a hook device loosely journaled on said eccentric cam adapted to swing 130 thereon from a position where it does not overlap the second of said first mentioned members to a position where it does so, means limiting the swing of the hook device so that it moves through a shorter arc than the lever, and a frictional contact device carried by the lever adapted to temporarily engage the hook as the lever swings through the hook's arc of movement to carry said hook with it, the eccentric cam being so located with reference to the hook that when the hook has reached its extreme position, overlapping the second of said first mentioned members, it draws said hook in the direction of the member on which the lever is pivoted.

cated with reference to the hook that when the hook has reached its extreme position, overlapping the second of said first mentioned members, it draws said hook in the direction of the member on which the lever is pivoted, this in combination with a spring device mounted in the member which does not carry the lever, adapted to be engaged by said hook prior to its reciprocation, whereby said reciprocation of the hook toward the member carrying the lever compresses the spring mechanism, thus securing the first two mentioned members together.

18. In a device of the class described, in combination with a case and cover, a lever pivoted on the case adapted to swing through a relatively wide arc, an eccentric cam carried by said lever, a hook journaled on said eccentric cam, means limiting the path of travel of said hook to an arc substantially less than the path of travel of the lever, a spring device carried by the cover and engageable by the hook in one position during its said path of travel adapted, when compressed, to assist in holding the cover on the case, a cam track on the free end of the hook, a plunger device mounted on and reciprocatable lengthwise of the lever, means urging said plunger toward the pivot of said lever adapted to bear upon said cam track on the hook, the whole so arranged and proportioned that when the hook has been swung away from the position where it engages said spring device and said lever is then moved toward said spring device, the plunger device will move the hook in unison with the lever into engagement with the spring device and hold it there until the eccentric cam which is so positioned for the purpose as to tend to draw the hook device toward the pivotal axis of the lever against the action of said spring device begins to so act for the purposes set forth.

19. In a device of the class described, the combination of a box member adapted to have an interfitting member secured thereto, a lever pivoted on the box member, an eccentric cam carried by said lever, a hook

mounted on said eccentric to rotate with the lever and be reciprocated toward the box member by the eccentric, means limiting the path of travel of the hook to an arc substantially less than the path of travel of the lever, a cam track on the free end of the hook, and a spring plunger device on the lever adapted to frictionally engage said cam track on the hook, whereby, as the lever travels over the arc of travel of the hook, it moves said hook in unison with it.

20. In a device of the class described, a lever member having an elongated slot intermediate between its ends, said slot being wider at one end than the other, the narrower portion having parallel sides, a plunger head notched to slide between said narrower parallel sides and having a stem extending toward said enlarged portion of the slot, a spring device located in the large portion of the slot controlling said stem and consequently the plunger head, and an in-closing case for the spring for the purposes set forth.

21. In a device of the class described, the combination of a lever having cut in it two parallel sided slots placed end to end and communicating one with the other, one slot being wider than the other, a plunger wider than the thickness of the lever and notched so as to be slidable in the narrower of said slots and yet of such a diameter that it may pass into the larger of said slots, a stem on said plunger head reciprocatable with the plunger longitudinally of the lever, a spring device located in the wider slot pressing said plunger stem, and cover devices retaining the spring in place, the whole arranged and disposed substantially as shown and described for the purposes set forth.

In witness whereof, I have hereunto subscribed my name in the presence of two witnesses.

LYMAN C. DAVIDSON.
